148,272

DESIGN FOR A PUPPET

Bil Baird, New York, N. Y.

Application March 6, 1947, Serial No. 137,400

Term of patent 14 years

(Cl. D34—2)

To all whom it may concern:

Be it known that I, Bil Baird, a citizen of the United States, resident of New York city, New York, have invented a new, original, and ornamental Design for a Puppet, of which the following is a specification, reference being had to the accompanying drawings, forming a part thereof:

Fig. 1 is a front view of a puppet showing my new design; Fig. 2 is a side view of a puppet thereof.

I claim:

The ornamental design for a puppet, as shown.

BIL BAIRD.
